UNITED STATES PATENT OFFICE.

EMILE B. LEVEY, OF FLUSHING, NEW YORK.

TICKET-HOLDER.

1,167,908.

Specification of Letters Patent. Patented Jan. 11, 1916.

Application filed December 1, 1914. Serial No. 874,976.

To all whom it may concern:

Be it known that I, EMILE B. LEVEY, a citizen of the United States, residing at Flushing, in the county of Queens and State 5 of New York, have invented new and useful Improvements in Ticket-Holders, of which the following is a specification.

My invention relates to devices for use of travelers, and particularly to means for 10 securely holding railway tickets in position upon the person of the owner so that they may readily be seen and punched by the conductor or other officer of the road.

The principal objects of the invention are 15 to provide a device which will securely hold the ticket or tickets and protect the owner against loss thereof; which will have separate accommodations for each of a plurality of tickets; which is so constructed as to 20 guide a ticket into its holding position and thereby facilitate its insertion into the device by the conductor; which will securely grip the ticket when inserted; and which will hold the ticket always in sight of the 25 gate attendant of the railway station and the conductor of the train, thereby saving time of and avoiding annoyance to both the traveler and the officers. These and other objects, and the advantages, of the invention 30 will more fully appear hereinafter.

The invention is illustrated in the accompanying drawings, and resides in the novel construction and arrangement of parts of a ticket holder hereinafter described and 35 claimed.

In the drawings, Figure 1 is a front view in elevation of a ticket holder; Fig. 2 is a reverse or rear view of the same; Fig. 3 is a transverse section taken on the line 3—3 of 40 Fig. 1; Fig. 4 is a longitudinal vertical section taken on the line 4—4 of Fig. 1; and Fig. 5 is a view similar to Fig. 4 showing a ticket in position.

Referring to the drawings, A is a body 45 plate preferably of sheet metal and shown as substantially circular in outline, although it may be given any desired outline other than that shown. At its upper end plate A is cut away as shown at a, this feature being 50 for the purpose hereinafter specified.

Located upon body plate A is a tongue B projecting obliquely from the face thereof at a slight angle so as to receive a ticket 55 between this tongue and the body plate.

Tongue B is attached to plate A at b, and

is preferably formed integral with the plate by being punched therefrom and then bent outwardly into the position shown. Tongue B is preferably formed with a notch upon each side thereof so that the tongue is wider 60 at its base and at its detached end than at the central portion. This may be produced by forming the cuts by which the tongue is struck from the body plate in the form of obtuse angles b¹ with sides b² extending to or 65 into proximity to the respective ends of the tongue.

Adjacent the tongue and upon each side thereof is formed a projection C which extends outwardly from the face of the body 70 plate and toward the tongue. In the embodiment of the invention illustrated these projections C correspond in outline to the two edges of the tongue and extend into the obtuse angle at the central portion thereof. 75 At this point the projections have their greatest altitude from the plane of the surface of the body plate, indicated at c, and here they are slightly flattened so as to produce no abrasion of the ticket when inserted 80 between the tongue and the projections.

On the reverse side of the body plate I provide an additional holding means for a ticket, this comprising a wire member D which is preferably bent to the general outline or contour of the body plate and is secured thereto at its lower ends d by soldering or otherwise. The wire member D stands at a slight oblique angle from the body plate so as to provide a holding space 85 between the two.

Both the body plate and wire member, as well as the tongue, are preferably of spring metal.

Suitable means are provided for attaching the device to a support such as the coat of the user, this means being shown as a pin E secured to the upper portion of wire member D.

It will be observed that owing to the cut 100 away portion a of the body plate, the wire member D extends considerably above the same, this being for the purpose of guiding the ticket into the space behind the body plate when it is desired to hold a ticket 105 therein, thereby avoiding any fumbling or catching of the ticket upon the upper edges of the device.

In the use of the device it is attached to the coat or clothing of the wearer in such 110

a position as to be visible to the gate attendant of the railway station or the conductor of the train. The ticket is inserted behind tongue B, sufficient force being used 5 to spring the tongue outwardly slightly when the ticket engages the rear face of the tongue and the outer surface of projections C. These latter by reason of their position within the notches at the sides of the tongue 10 cause the bending of the ticket at this point and it is securely held between the tongue and the projections. In this way the ticket is so firmly held as to protect the owner against loss, but it may be readily removed 15 either by the gate attendant or the conductor for the purpose of inspection or punching.

When an additional ticket is used the receiving space behind the body plate may be utilized, or this may be done of course 20 when only one ticket is used.

By the use of my device the traveler is saved considerable annoyance and both the traveler and the employees of the railroad are saved a good deal of time and trouble in 25 handling of tickets. The ticket is always ready when it is wanted, and in passing through the gate of a station the traveler is saved the trouble of setting down his baggage for the purpose of removing his ticket 30 from his pocket for the purpose of inspection by the gate attendant.

This holder may also be used to advantage at all functions where tickets are presented, such as balls, theater, race-track, etc.

Now that I have described a specific embodiment of my invention I wish it understood that various changes and modifications thereof may be devised without departing from the scope of the invention.

For instance, other materials than sheet metal may be employed, and the form and outline of some of the parts may be varied. All such changes I congregate as falling 40 within the scope of the invention.

Having described my invention what I 45

claim as new and desire to secure by Letters Patent of the United States is:—

1. A ticket holder comprising a body plate, a tongue fast thereon and obliquely projecting therefrom and having notched 50 sides, and a projection from said body plate upon each side of and adjacent said tongue opposite said notches.

2. A ticket holder comprising a sheet metal body plate, a tongue punched from 55 and obliquely extending therefrom and having notched sides, and a projection upon each side of and adjacent said tongue opposite said notches formed up from said body plate material.

3. A ticket holder comprising a sheet metal body plate, a tongue punched therefrom by cutting opposite and reversely arranged obtuse angle slits, the lower end of said tongue forming the attachment to the 65 body plate and the upper end thereof extending obliquely from said body plate, and a projection upon each side of and adjacent said tongue formed up from the body plate material at the other side of each slit within 70 the obtuse angle.

4. A ticket holder comprising a body plate of substantially circular outline, a tongue fast thereon and obliquely projecting from one face thereof, an additional 75 holding means comprising a spring wire member secured upon the reverse side of said plate and bent to the circular outline of the latter, said plate having a cut away upper portion so as to present an upper 80 edge below the upper portion of said circular additional holding member.

In testimony whereof I have hereunto set my hand in presence of two subscribing witnesses.

EMILE B. LEVEY.
